(57) **CLAIM**

The ornamental design for a slip-resistant outsole tread pattern, as shown and described.

DESCRIPTION

FIG. 1 is a perspective view of a section of the slip-resistant outsole tread pattern of the instant invention;

FIG. 2 is a top view of FIG. 1;

FIG. 3 is a side view of FIG. 2, all side views forming the same image thereof;

FIG. 4 is an enlarged perspective view of a section of FIG. 1;

FIG. 5 is a top view of FIG. 4;

FIG. 6 is a side view of FIG. 4, all side views forming the same image thereof;

FIG. 7 is a perspective view illustrating a shoe sole depicting the slip-resistant outsole tread pattern of the instant invention; and,

FIG. 8 is an enlarged cross-section perspective view of the slip-resistant outsole tread pattern depicted in FIG. 7.

The portions of figures illustrated in broken lines are for environmental purposes only and form no part of the claimed design.
